UNITED STATES PATENT OFFICE.

ELISHA JOHN ESMAIL, OF CHICAGO, ILLINOIS, ASSIGNOR TO THE OPERATORS PIANO COMPANY, INC., OF CHICAGO, ILLINOIS, A CORPORATION OF ILLINOIS.

MUSIC-ROLL CLEANER FOR PLAYER PIANOS.

Application filed December 3, 1925. Serial No. 72,970.

This invention relates to improvements in pneumatically operated musical instruments, and particularly to pneumatically operated pianos, now commonly called player-pianos.

Generally stated, the primary object contemplated by the present invention is to provide an attachment for such instruments, and particularly the player-piano, which will remove from the music roll or other control means, all dust, dirt or other foreign matter, before said roll reaches a point in its travel through the instrument where the foreign matter can gain access to the interior working parts of the instrument. As is well understood the player-piano is usually provided with what is termed a tracker board or bar having a series of orifices therein over which the perforated music roll passes to actuate, by vacuum or suction, proper mechanisms for producing the desired tones and the object of the invention, more specifically expressed, consists in providing an attachment which will remove from the surface of said music roll next the tracker bar all foreign matter before said roll passes over the orifices in the bar.

With these and other objects in view the invention consists in certain novel details of construction, combinations and arrangements of parts, all as will be hereinafter more fully described and the novel features thereof particularly pointed out in the appended claim.

In the accompanying drawings,—

Figure 1 is a front elevation illustrating more or less diagrammatically the tracker bar and the preferred embodiment of the present invention.

Fig. 2 is an end view of the tracker bar and attachment, the connections for producing the vacuum for cleaning the music roll and the receptacle for collecting the foreign matter being omitted in this view.

Fig. 3 is a sectional view on the line 3—3 of Fig. 1, the vacuum producing connections and trap for foreign matter also being omitted.

Fig. 4 is a sectional view of the trap or collector for particles of foreign matter removed from the music roll.

No particular form of tracker bar is required in the present invention and for this reason the tracker bar 10 is illustrated more or less diagrammatically in the accompanying drawings. Extending longitudinally of this tracker bar is a series of orifices 11, usually eighty-eight in number, over which the

perforated music roll is adapted to travel, the several orifices remaining sealed until a perforated portion of the music roll moves into registry with one or more of them whereupon the desired tones will be produced by pneumatically operated mechanisms in the usual way and in a manner well understood in the art. These mechanisms for producing the tones form no part of the invention and for this reason it is not deemed necessary to illustrate them. The music roll 12 is shown extending from roller 13 over the tracker bar to a take-up roller 14 and at the rear of the tracker bar there is a series of conduits 15 corresponding in number to the orifices in the tracker bar and communicating with said orifices for connection to the suction producing devices in the well known manner.

A vacuum is present at all times in each of the orifices 11, and, for this reason, if there should be any dust or any other foreign matter on the surface of the music roll passing over the tracker bar, such foreign matter will, of course, be drawn into said orifices and ultimately into the pneumatics, the primaries, chests, and pumps, and into the bleat holes of the pneumatics and primaries, ultimately clogging up such elements causing them to become sluggish, and possibly preventing them operating or functioning properly. In view of this the present invention contemplates the provision of means, preferably pneumatically operated, for removing from the surface of the music roll which contacts with the tracker bar 10 all particles of dust and foreign matter before said roll passes over the tracker bar. This may be accomplished by providing a vacuum chamber having an entrance slot located adjacent to but in advance of the orifices 11 in the tracker bar. Such chamber might be formed in various ways but in the preferred embodiment, which is illustrated in the present instance there is a hollow casing 16 located immediately to one side of the tracker bar 10 in such position that the music roll will contact with it in passing over the same and over the bar. Formed in the face of said casing 16, with which the roll contacts, is a slot 17 extending parallel with and to or beyond the ends of the series of orifices 11 and for producing a vacuum in said casing the latter is provided in one of its walls with a conduit 18 to which there may be connected a vacuum tube 19 leading to suction producing apparatus 110

which may be the same apparatus for producing the suction or vacuum in the orifices 11. With this construction it will be apparent that any foreign matter adhering to the 5 music roll will be removed from the surface of the latter as it approaches the orifices in the tracker bar.

To prevent such foreign matter reaching the suction producing apparatus, a suitable 10 trap or separator may be interposed in tube 19 leading to such apparatus. In the present instance this trap is shown as consisting of a base 20 having a chamber 21 formed therein in which there is a sieve or other separating 15 member 22, the section of pipe 19 extending from conduit 18 of casing 16 entering chamber 21 at one side of said separating member 22 and the section of pipe 19^a extending from base 20 to the suction devices communicating 20 with said chamber 21 on the opposite side of the separating member 22. The top of the

chamber 21 may be closed by a cover 23 removably held thereon by a clamping screw 24 extending through a yoke 25 secured on said base 20.

No particular means of attaching the casing 16 to tracker bar 10 are necessary, any desirable form of clips 26 sufficing for this purpose.

What I claim is:

In pneumatically operated musical instruments embodying a tracker bar having a series of orifices over which a music sheet is adapted to travel, a casing supported by said tracker bar and provided with a vacuum chamber, and having a slot extending longitudinally thereof the length of the orifices in the tracker bar, said casing located in advance of the tracker bar and over which the music sheet passes before passing over the tracker bar.
